UNITED STATES PATENT OFFICE.

ISAAC W. HEYSINGER, OF PHILADELPHIA, PENNSYLVANIA.

CROSSING-CONDUIT FOR ELECTRIC RAILWAYS.

SPECIFICATION forming part of Letters Patent No. 398,963, dated March 5, 1889.

Original application filed April 21, 1887, Serial No. 235,584. Divided and application filed November 29, 1887, Serial No. 256,396.
Again divided and this application filed May 24, 1888. Serial No. 274,884. (No model.)

To all whom it may concern:
Be it known that I, ISAAC W. HEYSINGER, of Philadelphia, in the county of Philadelphia and State of Pennsylvania, have invented a certain new and useful Improvement in Crossing-Conduits for Electric Railways, &c., of which the following is a full, clear, and exact description, reference being had to the drawings accompanying and forming a part of this specification, in which—

Figure 1 is an end view of a crossing-conduit in place embodying my invention, showing one of the passages in end view with the electric conductors and their connections and the current-gathering devices of an electric motor-car, and also the trackway and street surface, the transverse passage of the conduit being seen in side view. Fig. 2 is a horizontal section of Fig. 1 along the line of conductors A⁶ A¹⁶ B⁶ thereof, showing the track-supports of the frames J' J¹¹. Fig. 3 is an enlarged view of the middle part of Fig. 2, showing the insulating-tubes also which convey the electric current across the interrupted spaces of the longitudinal conductors; and Fig. 4 is a top view of my crossing-conduit, showing my electric leads projecting from the free ends of the passages thereof, the whole adapted to be attached to different series of continuous conduits approaching said crossing from different directions.

The lettering in all the figures is uniform.

My invention relates to the construction of a crossing-conduit for electric railways in which two intersecting railways require to have the current-gathering devices of each motor-car traverse the said intersection without interruption and without being put out of electric contact of the motor-dynamo of said car and the longitudinal conducting-leads of either of said railways.

My present invention, which forms the subject-matter of this application, except in some of the specific details relating to the insulation of my deflected wires at crossings, was embraced in my application for Letters Patent, Serial No. 256,396, filed November 29, 1887, from which it has been separated to make a divisional application, and my said application, Serial No. 256,396, filed November 29, 1887, was also embraced as to its subject-matter in my

original application, Serial No. 235,584, filed April 21, 1887; and my present invention is particularly applicable to the system and construction of my electric railways as therein shown, described, and claimed, but is also adapted for use with other electric railways, as may be desired.

The first part of my invention consists in a crossing-conduit for electric railways having two or more transverse passages through which the current-gathering devices of an electric motor can pass, said transverse passages opening laterally into each other and provided with insulators and longitudinal conducting-leads, said leads interrupted at said intersection and the free ends of said leads joined by laterally-deflected wires carried in insulated ducts, the whole forming a single construction made in the shops, for instance, and complete when put down in place, the conduits of the main lines being simply attached to the free ends of the transverse passages of said crossing-conduit, the leads being electrically joined to the leads of the main lines at the same time, and the whole ready for use.

The second part of my invention consists in providing my crossing-conduit with laterally-projecting arms, said arms forming supports for the trackway of each system or line of railway crossing said conduit, so that the same may be locked securely without possibility of displacement by the trackways of the intersecting railways, each acting against displacement by the others.

The third part of my invention consists in the means by which I carry my insulated leads through the walls of my crossing-conduit and connect them by laterally-deflected wires carried in insulated ducts from the free end of one interrupted lead to the corresponding free end of the same lead beyond said intersection.

My invention also consists in the special construction of my leads, supports, insulators, cruciform conduit-slot, and other details of construction, in the combination as herein-after described.

Referring to the drawings, Figs. 2 and 4 show the crossing-conduit or intersection which forms the subject-matter of my pres-

ent invention, and which I use in my electric railway, and, as shown in the figures, I make these crossing-conduits complete and ready for use before I put them into the ground or 5 lay the trackway upon them. It is cross-shaped in horizontal section, open in the two transverse directions occupied by the intersecting lines of railway, each transverse conduit having a narrow slot in its upper surface, which slots intersect each other at the 10 middle and form a cruciform slot, one branch giving passage into the conduit for the current-gathering devices of the motor-car of each line of railway and allowing free passage therefor. To the inner sides of the frame of the conduit, along each transverse passage, I attach insulated conducting-leads, which terminate near the inner angles formed by the intersecting conduits, and from the termination of each lead I carry across the interrupted space an outside conducting-wire adapted to permit the free passage of current-gathering devices along the transverse passage, which said outside wire is attached to 25 the opposite free end of the continuation of the same lead beyond the said intersection, so as to complete the circuit along the conducting-leads of the railway just as though the same were made continuous from end to 30 end. These laterally-deflected wires I carry in insulated tubes or ducts, which I prefer, as described in my former original application, to make of leaden pipes, (see Fig. 3,) in which the wires are securely carried and properly 35 insulated by suitable packing between the said wires and the inner surfaces of the said ducts. I carry these leaden pipes through the walls of the conduit to make connection with the ends of the interrupted leads, or I 40 provide the insulating-block which supports the free end of the lead with a tubular projection extending outward through the wall of the conduit, and to the outer ends of these tubular projections I attach the outside ducts 45 or leaden tubes and carry the deflected wires from the free ends of the lead through these tubular projections of the insulating-block and the ducts attached thereto.

The frame of the crossing-conduit, Figs. 1 50 and 2, is provided at each of its ends where the transverse passages commence with lateral flanges perforated with bolt-holes, so that when the conduits of the main line are placed against them the corresponding flanged faces 55 of the main and the crossing conduit will face each other, and bolts inserted in the holes will draw the two conduits together and make a secure construction. At the same time the leads of the crossing-conduit are joined to the 60 leads of the main conduit and the whole is ready for use.

At the internal corners of my crossing-conduit (see Figs. 2 and 3) I round off the free 65 ends of the leads, so that current-gathering devices may more freely ride up and make connection therewith as they pass the intersection.

L L' L', Fig. 2, are the transverse passages of my crossing-conduit, and L² is the space occupied by the intersection. The narrow slots J³ J¹², Fig. 4, are shown in Fig. 2 in dotted outline; but in Fig. 1 the same is shown in end view with the bar C of a motor-car extended down through the said slot and supporting wires c¹⁵ c¹⁶, which connect the current-gathering rollers c c' with the leads A⁶ B⁶, and transmit the electric energy to the motor-dynamo of the car above. Instead of rollers c c', other current-gathering devices may be employed. The leads A⁶ B⁶ are supported 80 upon longitudinal wooden bars A B and insulated at various distances by the insulating-blocks I I I, all of which construction is fully described and claimed in my application for Letters Patent, Serial No. 256,396, filed November 29, 1887; and in this application I make no broad claim to the devices therein shown, described, and claimed, but confine myself to the specific combinations involved in this application. 90

The insulating-blocks I I I are bolted to the inner walls of the conduit, Fig. 3, by bolts I² I² and the insulating-blocks I I, which are straight along the line, are made with an angle, as shown at I⁶ I⁶, where they are fitted 95 around the corners of the crossing-conduit. The tubular prolongations I¹⁰ I¹⁰ extend from the blocks I⁶ through the walls of the conduit, and to the outer ends are attached leaden tubes K K' K', which extend across the intersection, as shown at K, Fig. 1, where the leaden tube is seen beneath the conduit. Other substances, as concrete, asphaltum, wood, &c., may be used for these lateral tubes or ducts, or in some cases the wires themselves may be 105 heavily insulated and be used without any separate outer casing or tube. The ends of these tubes are securely attached to the tubular projections I¹⁰ I¹⁰ of each side, and in Fig. 3 (lower part of figure) I do not provide the blocks I⁶ I⁶ with such tubular projections I¹⁰, but carry the leaden tube K' directly through the conduit-wall and through a perforation 110 in the insulating-block I⁶ and secure it by a flanged expansion, K', or a cemented joint 115 upon the inner side. This latter method is cheaper, and I prefer to use it in this construction.

The walls of the conduit J J J¹⁰ J¹⁰ are provided at their free ends with flanged expansions J⁶ J⁶ J¹⁶ J¹⁶, having bolt-holes J⁷ J⁷ J¹⁷ J¹⁷ for attachment to similar flanged expansions upon the ends of the main conduits with which the crossing-conduit is to be used. Instead of these flanged expansions, the ends 125 may be made to taper and slip over or inside the free ends of the main conduit and be held by suitable cross-bolts; but the construction shown is preferable, unless for special reasons which may arise. 130

The cross-shaped intersection-conduit I prefer to provide near its free ends with lateral supporting-arms, as shown in the conduits of my other pending application hereinabove

described, and which support the stringers upon which the rails or cross-ties of the railway are placed; but in my present invention I unite the free ends of these supporting-arms $J' J'' J' J''$ at the corners $J^{20} J^{20}$, so as to greatly increase the strength and resistance of the supporting-arms as well as of the conduit itself.

J' and J'' are benches formed for the support of the stringers, as shown in Fig. 1.

My crossing-conduit, as a whole, I make of a single casting in one construction, and afterward attach the insulators, leads, side wires, &c., or I build it up of sheet metal, bolted or riveted together, and all ready for use, so that when placed in the ground, if it be subterranean, or placed upon the substructure, if for an elevated railway, it will be all ready to make connection with the conduits of the main lines as they are built to approach it; but I do not confine myself to such construction put in place as a whole, but sometimes build my conduit from separate parts in the place which it is to occupy. Instead of using separate side wires to carry the current between the free ends of the insulated leads, I sometimes carry these leads themselves bodily through the walls of the conduit, properly insulated and protected by heavy leaden or other ducts as they traverse the intersection beneath the conduit. I show this very clearly in Fig. 3, while in Fig. 2 are shown separate wires by which I accomplish the same result. I prefer to use the leads thus deflected, as continuity is better preserved and the caliber of the lead is not impaired in any part. These leads, whether flat or round in cross-section, are easily deflected and carried across the interrupted space, and if suitably wrapped with insulating material and passed into a leaden pipe, paraffine being poured into said leaden pipe, will fix all in place and allow the same to be bent at will. Instead of paraffine, other insulating substances may be used, and I thus prefer to treat my side connections when placed in their tubes or casings with an insulated wrapping and a covering of melted paraffine, or its equivalent, poured into the said tube and allowed to cool. This melted paraffine is very readily poured in at the flanged opening K^5 , as shown in Fig. 3, after the lead B^6 has been wrapped and the wrapped portion passed through the tube K^5 , and upon its emergence at the opposite end thereof carried on to make the continuation of the said lead B^6 beyond the intersection.

I do not in this application limit myself specifically to the precise construction herein shown, but combine the various parts of my invention or adapt one to another in various ways known to mechanics skilled in the art, without departing from the principles of my invention, as herein set forth, and for some of the details of the parts with which my said invention is particularly adapted to be used I refer to my other applications for Letters

Patent hereinabove referred to and now pending.

Having now described my invention, what I claim, and desire to secure by Letters Patent, is—

1. As an article of manufacture, a crossing-conduit for electric railways for use at intersections thereof, formed in a single construction, practically complete before being put into place, said conduit having two transverse passages crossing at an angle and opening into each other, provided with longitudinal slots along their upper surfaces, intersecting and opening into each other, said passages having secured to their inner and opposite sides parallel conducting-leads for each intersecting line $A^6 B^6 A^{16} B^{16}$, interrupted by the distance between the internal corners of said transverse passages, and having the free ends of the conductors of said leads joined to their continuations beyond said interrupted space by deflected and insulated metallic conductors carried across said intersection out of the line of travel of the current-gathering devices of a motor-car upon either line of railway, said leads attached to the inner sides of said conduit by insulated supports, the free ends of said leads at the extremities of the passages and the outer ends of said passages adapted to be attached to the free ends of the leads and the free ends of the passages of the conduits of said railways, so as to complete the said intersecting railways and the electric connections thereof when the said conduit is in place, substantially as described.

2. The railway-crossing conduit having transverse passages open through the same and intersecting each other, longitudinal open slots along its upper surfaces intersecting each other, and a supporting frame-work, $J' J''$, for the rails of an intersecting railway, the whole formed in one construction before being put into place for use, substantially as described.

3. In a crossing-conduit for electric railways, the transverse intersecting passages $L L'$, having walls $J J''$, said passages crossing each other at an angle, in combination with supporting-arms $J' J'' J' J''$, springing from the outer walls of said passages and having their free ends united at $J^{20} J^{20}$, the whole forming a rigid square frame-work adapted to support the trackway of two intersecting railways and prevent displacement of the said conduit by the thrust of said railways in either direction, together with a line of electric leads extended along said passages, insulated from said walls, and interrupted at said intersection, and laterally-deflected conductors bridging said interrupted spaces out of line of travel of the current-gathering devices of a motor-car upon said railways, substantially as described.

4. In combination with a crossing-conduit for electric railways, the intersecting passages $L L'$, having intersection L^2 , the leads $A^6 B^6$ along the sides of the passage L , and the leads

$A^{16} B^{16}$ along the sides of the transverse passage L' , said leads insulated from the conduit walls $J J^{10}$ and interrupted at said intersection L^2 , each of said leads substantially continuous and carried out laterally through the wall of said conduit and across said intersection beneath the same, and thence back through said wall into said passage beyond said intersection and continuously onward along the line, together with flexible insulating tubes or ducts $K K^3$, surrounding said leads and preserving the insulation thereof in their passage from the deflected end of each of said leads to the continuation of the same beyond said intersection, substantially as described.

5. In an electric-railway-crossing conduit, the transverse passages $L L'$, intersecting each other, in combination with the leads $A^6 B^6 A^{16} B^{16}$, extended along said passages and interrupted at the intersection L^2 thereof, said leads deflected, so as to cross the said intersection out of the line of passage of the current-gathering devices of a motor-car, and the insulating-tubes $K K' K^2 K^3$, surrounding said deflected leads, substantially as and for the purposes described.

6. In combination with the cross-shaped conduit having walls $J J J^{10} J^{10}$ and intersecting passages $L L'$, the electric leads $A^6 B^6 A^{16} B^{16}$, adapted to be connected with the corresponding leads of one or more electric railways, and the flanged expansions $J^6 J^6 J^{16} J^{16}$ upon the free ends of the walls of said cross-shaped conduit, and bolt-holes $J^7 J^{17}$ in said flanged expansions, the said flanges adapted to face against corresponding flanges of the

conduits of transverse lines of electric railway, and, bolted thereto through said bolt-holes, maintain the said leads and said cross-shaped conduit in place against thrust from either direction, substantially as described. 40

7. In an electric-railway crossing, in combination with the leads $A^6 B^6 A^{16} B^{16}$, insulated from their supports and adapted to supply electricity to the current-gathering devices of a motor-car traveling in contact therewith, the deflected wires $A^{11} A^{21} B^{11} B^{21}$, covered with an insulating substance and contained within ducts $K K' K^2 K^3$, carried across the intersection L^2 out of line of travel of said current-gathering devices, the space between said wires and said ducts filled with melted paraffine or the like after the said wires are in place in said ducts, substantially as described. 45 50 55

8. In an electric-railway-crossing conduit, conducting-leads extended along within the same, insulated from said conduit by insulators $I I^6$, and interrupted at the intersection L^2 , said leads deflected at said interruption to bridge the said intersection, or the free ends thereof connected by laterally-deflected wires, in combination with leaden tubes K^3 , or the like, surrounding and insulating said deflected wires, said tubes extended through perforations in said insulating-blocks $I^6 I^6$, opposite the free ends of said leads, and secured in said insulators I^6 by joints or expansions K^5 , substantially as described. 60 65
